United States Patent Office

Des. 187,560
Patented Mar. 29, 1960

187,560

BOTTLE

Leon Winter, Paris, France

Application April 10, 1959, Serial No. 55,456

Term of patent 14 years

(Cl. D58—8)

FIG. 3.

FIG. 1.

FIG. 2.

Fig. 1 is a front elevational view of a bottle, showing my new design;

Fig. 2 is a rear elevational view thereof; and

Fig. 3 is a top plan view thereof.

I claim:

The ornamental design for a bottle, substantially as shown.
